UNITED STATES PATENT OFFICE

152,851

DESIGN FOR A CHAIR SUPPORTING BASE

Chester J. Barecki, Grand Rapids, Mich., assignor to American Seating Company, Grand Rapids,
Mich., a corporation of New Jersey

Application March 27, 1947, Serial No. 137,943

Term of patent 3½ years

(Cl. D15—8)

To all whom it may concern:

Be it known that I, Chester J. Barecki, a citizen of the United States, residing at Grand Rapids, in the county of Kent and State of Michigan, have invented a new, original, and ornamental Design for a Chair Supporting Base, of which the following is a specification, reference being had to the accompanying drawing, forming a part thereof.

Figure 1 is a perspective view of a chair supporting base, showing my new design, the dotted and line representation of a chair seat and back being for illustrative purposes only;

I claim:
The ornamental design for a chair supporting base, substantially as shown and described.

CHESTER J. BARECKI.
